EYECUP

Herbert L. Magill and Morris L. Duskin, Chicago,
Ill.; said Duskin assignor to said Magill

Application December 22, 1938, Serial No. 247,172

5 Claims. (Cl. 128—249)

This invention relates to eyecups, and its purpose is to provide a construction by which the water, medicine or other washing fluid employed therein can be more effectively applied to the eyeball and distributed thereover than with the present structures. Another object is to provide a design which can be economically manufactured, and which shall be convenient to assemble and to use. The invention consists of certain features and elements of construction, as herein shown and described and as indicated by the claims.

In the drawing:

Fig. 1 is a plan view on an enlarged scale looking into the eyecup embodying this invention and showing the ports through which the liquid is fed into the same when in use.

Fig. 2 is a side elevation of the eyecup, but on a smaller scale than Fig. 1.

Fig. 3 is an end elevation of the same.

Fig. 4 is a section taken as indicated at line 4—4 on Fig. 1.

Fig. 5 is a transverse section taken as indicated at line 5—5 on Fig. 1.

Fig. 6 is a sectional view similar to Fig. 4 showing a modified construction.

The eyecup which is commonly in use at the present time comprises simply a bowl having a rim whose contour is approximately oval, and which is formed to fit snugly around the eye. The bowl is partially filled with the solution or medicine to be employed as an eye wash, and is placed against the eye in horizontal position. It is then necessary to tilt the head back to invert the eyecup, so that the liquid shall be carried by gravity onto the eye and over the surface thereof as well as possible. Many persons with sensitive eyes involuntarily close the lid upon the first contact of the solution, thus reducing the effectiveness of the treatment. And, frequently, the edge of the cup does not fit the contour of the face so closely as to prevent a considerable leakage around the edge when the cup is inverted in use.

The present invention provides for distributing the liquid eye wash over the eyeball repeatedly, if desired, without inverting the cup, thus reducing the likelihood of such leakage around the edge of the cup; and it also provides for discharging the liquid against the eyeball with a moderate degree of force, and, preferably with a whirling motion, so as to increase the effectiveness of the washing action. In addition, the forcible discharge of the liquid toward the eyeball can usu-

ally be accomplished in a manner which will avoid the involuntary closing of the lid.

The structure which embodies this invention consists of a bowl portion 1 having its rim 2 and body portion of the usual contour of an eyecup; but instead of the bottom of the bowl being closed, it includes a rim flange 3 to which there is secured a compressible hollow bulb 4 preferably of rubber, having a thickened rim 5 which engages the groove 6 of the flange 3. The provision of the groove 6 in the flange 3 involves the formation of a bead 7 with which the thickened portion or bead 5 of the bulb interlocks, as clearly seen in the sectional views. The cavity of the bulb 4 communicates with the interior of the bowl 1 through a plurality of ports 8—four such ports are shown in the drawing. Each of the ports extends obliquely with respect to the central axis of the device, and its walls are inclined in a generally helical direction. Thus, when the bulb 4 is filled with liquid and compressed, the liquid is expelled therefrom through the ports 8 toward the eyeball, with a whirling circulating motion, which serves for effectively cleaning and washing the surface of the eye. At the same time, the bowl 1 confines the liquid closely to the eye, and there is almost no chance for leakage around the rim 2.

Preferably, the bowl 1 and the features integrally associated therewith, may be constructed of plastic material, such as Celluloid, Bakelite, Pyrolin or the like, so that it may be molded in final form, which will not require any finishing work. And to permit of this method of manufacture the ports 8 may be so designed around a central hub 9 that they may be formed by suitable molding cores (not shown) which will be withdrawable in the molding operation in opposite directions parallel to the central axis of the hub 9. As seen in Fig. 1, each of the inclined or helical partitions 10 terminates in the bowl 1 at a radial edge 11. Each port extends downwardly and spirally through substantially a quarter-turn, and opens into the bulb 4. Thus, the oppositely withdrawable cores may contact with each other, face to face, at the radial planes of the edges 11 so as to make each of the inclined passages continuous for connecting the bulb 4 with the bowl 1. This is merely one suggested method of manufacture, and it will be obvious that substantially equivalent inclined passages may be formed in other ways, so that the liquid propelled through them by the compression of

the bulb 4 will emerge into the bowl 1 with the desired swirling motion.

Fig. 6 illustrates a slightly modified construction in which the bowl 1^x and the bulb 4^x are formed integrally with a connecting neck portion 3^x into which a molded disk 13 may be snapped and held by the elasticity of the material comprising the bowl and bulb. Preferably, this material will be rubber, so that the bulb shall be compressible, in the manner already described. The partition disk 13 may have ports 8^x similar in formation to those shown in Fig. 4, so that the liquid passing from the bulb 4 into the bowl 1 will acquire a whirling movement for the purpose already explained.

It will be recognized that the compressible bulb might be connected with the eyecup through a flexible tube, or that some other form of pumping device might be supplied in place of the bulb, but, for economy and ease of manufacture, as well as for simplicity of construction, rendering the device easily cleaned and therefore sanitary, we find that the bulb connected directly to the eyecup is the most satisfactory arrangement, and, incidentally, is most economical in the use of the solution employed as an eye wash therein. Therefore, while there is shown and described herein certain specific structure embodying the invention, it will be manifest to those skilled in the art that various modifications and re-arrangements of the parts may be made without departing from the spirit and scope of the invention, and that the same is not limited to the particular form herein shown and described, except insofar as indicated by the appended claims.

We claim:

1. An eyecup having its wall opposite the open side of the cup composed of a plurality of substantially helical partitions spaced apart at intervals around a central hub to form a plurality of inclined passages leading through said wall, whereby a whirling motion is imparted to liquid forced into the cup through said ports.

2. The combination of an eyecup having its

wall opposite the open side of the cup composed of a plurality of substantially helical partitions spaced apart at intervals around a central hub to form a plurality of inclined passages leading through said wall, together with a flexible and collapsible bulb attached to the eyecup and communicating therewith through said passages, whereby a whirling motion is imparted to liquid transferred from the bulb to the cup by pressure operating to forcibly collapse said bulb. 10

3. An eyecup having an inlet passage extending through the bottom wall of the cup and opening into said cup at the surface of said bottom wall, said passage extending in circumferential direction about the central axis of the cup and obliquely with respect to a plane perpendicular to said axis, whereby a whirling motion is imparted to liquid forced into the cup through said passage and a whirling motion is thereby transmitted to liquid already in the cup. 20

4. An eyecup having an inlet passage extending through the bottom wall of the cup and opening into said cup at the surface of said bottom wall, said passage extending obliquely with respect to a plane perpendicular to the central axis of the cup and being spaced radially from said axis, together with a flexible and collapsible bulb attached to the eyecup and communicating therewith through said passage, whereby a whirling motion is imparted to liquid transferred from the bulb to the cup by pressure operating to forcibly collapse said bulb. 30

5. An eyecup having a pair of inlet passages extending through the bottom wall of the cup and opening into said cup at the surface of said bottom wall, said passages being disposed at opposite sides of the central axis of the cup and extending respectively in oppositely oblique relation to a plane perpendicular to said axis, whereby a whirling motion is imparted to liquid in the cup by liquid forced into the cup through said passages simultaneously. 35
